(57) CLAIM

We claim the ornamental design for a tradeshow display crate, as shown and described.

DESCRIPTION

FIG. 1 is a front left perspective view of a tradeshow display crate, showing our new design;

FIG. 2 is a back right perspective view of the tradeshow display crate;

FIG. 3 front perspective view of the tradeshow display crate in an expanded display configuration; and,

FIG. 4 is a back perspective view of the tradeshow display crate in an expanded display configuration.

The broken line portions of the figure drawings show portions of the article that form no part of the claimed design.
